GUN CARRIAGE

Elmer C. Goebert, United States Army,
Philadelphia, Pa.

Application February 24, 1932, Serial No. 594,797

3 Claims. (Cl. 89—40)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a gun carriage.

In wheeled gun carriages it is a common expedient to emplace the carriage for firing by substituting a fixed support for the wheels. The purpose of the present invention is to provide a 10 firing support that is associated in a novel manner with the wheels and the brake mechanism for the wheels.

To these and other ends, the invention consists in the construction, arrangement and combination of elements described hereinafter and pointed out in the claims forming a part of this specification.

A practical embodiment of the invention is illustrated in the accompanying drawings, 15 20 wherein:

Fig. 1 is a view in side elevation of the improved gun carriage shown in the travelling position.

Fig. 2 is a similar view of the carriage emplaced 25 for firing.

Fig. 3 is a plan view of Fig. 1 with the gun removed.

Fig. 4 is a view in elevation of the inside of the right wheel.

30 Fig. 5 is a vertical sectional view through the wheel of Fig. 4, and showing the axle in rear elevation.

Fig. 6 is a sectional view on the line 6—6 of Fig. 4.

35 Fig. 7 is a sectional view through the clamp.

Referring to the drawings by characters of reference, there is shown a gun carriage consisting essentially of a trail A, axle B connecting braces C and wheels D. In the present instance the 40 axle includes depending crank arms 5 for the purpose of lowering the spindles 6 on which the wheels are mounted.

As shown in Fig. 5 the hub 7 of each wheel is formed internally with a flange 8 on which a 45 brake drum 9 is secured by means of bolts 10. A peripheral recess 11 in the flange is closed on one side by the brake drum and in the groove thus provided is rotatably mounted a segment 12. The segment is formed with an offset 13 to clear 50 the tire 14 on the wheel and on its outer edge is secured an arcuate shoe 15 overlying the tire 14 and spaced therefrom.

On the end of the segment opposite to the shoe there is secured a bracket 16 threadedly mounting 55 a clamp 17. A shoe 18 loosely mounted on the clamp is adapted to engage the brake drum and has a lug 19 extending along the outer face of the drum. When the segment is in the lower or firing position (Fig. 2) it is locked to the brake 60 drum by means of the clamp.

The brake mechanism is of a conventional internal expanding type and includes a backing plate 20 for the drum that is secured to the crank 5 of the axle by means of bolts 21. A hand lever 22 carrying a holding rod 23 engageable 65 with a rack 24 is secured to the outer end of the usual actuating shaft 25.

Referring to Fig. 6 an arm 26 secured to the backing plate extends over the brake drum and carries a casing 27 in which is mounted a spring 70 pressed latch 28. The latch is adapted to engage in an aperture 29 in the segment 12 to hold it in the raised or travelling position.

In emplacing the carriage for firing the segments are unlatched and allowed to fall to the 75 ground behind the wheels. The rear of the trail is then raised, the segments are locked to the brake drum by acting on the clamps 17 and the brake drum is locked to the axle unit by acting on the hand levers 22. The segments and trail 80 are thus made to form a rigid unit and when the trail is lowered to the ground the carriage will rotate on the arcuate shoes 15. The parts will then be in the position shown in Fig. 2. This operation is reversed when the segments are to be 85 restored to the travelling position.

I claim:

1. In a gun carriage, an axle, a trail on the axle, wheels on the axle, a brake drum on each wheel, brake actuating mechanism carried by the 90 axle, a segment rotatably mounted on the hub of each axle and retained by the brake drum, a shoe carried by each segment and overlying the wheel in spaced relation thereto, means on the axle for holding the segment in inoperative position and means for clamping the segment to the 95 brake drum.

2. In a gun carriage, an axle, a trail on the axle, wheels on the axle, a brake drum on each wheel, brake actuating mechanism carried by 100 the axle, a segment rotatably mounted on the hub of each axle, a shoe carried by each segment and overlying the wheel in spaced relation thereto, means on the axle for holding the segment in inoperative position and means for clamping the 105 segment to the brake drum.

3. In a gun carriage, an axle, wheels on the axle, a drum brake mechanism for each wheel, an 110 emplacing member pivotally mounted on the hub of each wheel, and means for locking the emplacing member to the corresponding brake mechanism.

ELMER C. GOEBERT.
